[57]

ABSTRACT

A deflection circuit for an electron beam formed with an electrode system suitable for both focussing and deflection, which system includes an electrode dividend in segments. The electrode segments are incorporated in a bridge circuit built up from resistors while two deflection signal generators are each connected to two bridge connection points. A focussing voltage source is connected to a central connection point of a bridge cross branch so that the source and the generators are mutually decoupled.

DEFLECTION CIRCUIT FOR AN ELECTRON BEAM IN A CATHODE-RAY TUBE

The invention relates to a deflection circuit for an electron beam in a cathode-ray tube, which circuit is provided with an electrode system suitable for both focussing and deflecting the electron beam for which purpose the system comprising an electrode divided in segments is connected to a focussing voltage source and to two deflection signal generators for deflection in two transverse directions relative to the tube axis.

U.S. Pat. No. 2,911,563 describes a cathode-ray tube which is formed with a system of electrodes for both focussing and deflecting the electron beam. Since one of the electrodes of the system is divided in segments, different voltages can be applied to the electrode segments. The mean value of these voltages across the electrode segments relative to the voltage across a different electrode in the system determines focussing. The difference between the voltages across the segments yields a field strength at right angles to the axis of the tube so that the electron beam is deflected.

Apart from the extent to which both focussing and deflection according to said patent specification could be effected in a satisfactory manner, which is not quite satisfactory because the specification states that the deflection is only small and can be used for correcting purposes, it is not at all described how the electrode system is to be connected to the focussing source and to the deflection signal generators so as to cause the circuit to fulfil its dual task.

An object of the invention is to provide a deflection circuit with which a satisfactory focussing and a satisfactory deflection can be obtained, while the control of the electrode system is as simple as possible without mutually unwanted influences of the various voltage sources and signal generators.

To this end the deflection circuit according to the invention is characterized in that when a bridge circuit having bridge branches between four bridge connection points is used for the deflection, of which points each facing pair is connected between two connection terminals of each different deflection signal generator and in which the branches include resistors and further connection points focussing is effected by providing at least a cross branch formed with resistors and connection points in the bridge, which cross branch has a central connection point for connection to the focussing voltage source.

It is to be noted that it is known per se from French Patent Specification No. 1,368,473 to supply an electrode system composed of bar-shaped segments and being solely intended for the deflection, from a bridge circuit formed with bridge branches between the four connection points and being provided with resistors and connection points. In this case, however, the problem of focussing to be performed in a combined manner does not at all occur.

The application of the focussing voltage according to the invention to a symmetry point made through the cross branch or branches has the result that ever present segment leakage currents do not cause asymmetrical errors.

The invention will be further described with reference to the following Figures as examples in which

FIG. 1 diagrammatically shows a cathode-ray tube, which is provided with a system of electrodes for both

focussing and deflecting and with control means therefor,

FIG. 2 shows a schematic circuit diagram of the control means formed according to the invention, suitable for use with an electrode divided in eight segments.

FIG. 3 shows, likewise as FIG. 2, a bridge circuit with which deflection error corrections can be performed, and

FIG. 4 shows, likewise as FIG. 2, a bridge circuit which is suitable for use with an electrode divided in six segments.

Corresponding components in the various Figures are denoted by the same reference numerals in so far as this is useful.

15 FIG. 1 shows a partial diagrammatic cross section of a cathode-ray tube K₁. A so-called target plate is denoted by K₂ in tube K₁. The target plate K₂ is scanned by an electron beam not shown which is generated by an electron gun K₃. K₄ denotes a tube axis of the tube

20 K₁. In order to cause the electron beam to scan the target plate K₂, while being satisfactorily focussed, a system of electrodes E consisting of three electrodes E₁, E₂ and E₃ is provided. The electrode E₁ is divided in eight segments S₁ . . . S₈ some of which are shown in 25 FIG. 1. In FIG. 2 all segments S₁ . . . S₈ of the electrode E₁ are shown in a cross-section which is at right angles to that of FIG. 1. The electrode segments S₁ . . . S₈ are located on the circumference of a circle along the wall of the tube K₁.

30 FIG. 1 shows that a voltage U_A is applied to the electrodes E₂ and E₃, which voltage is supplied by a direct voltage source (u) denoted by D_A. The electrodes E₂ and E₃ may alternatively receive different voltages. In case of a more positive voltage across the electrode E₃ the electrons are accelerated between the electrodes E₂ and E₃.

The eight segments S₁ . . . S₈ of the electrode E₁ are connected to a cable L provided with eight leads L₁ . . . L₈. All eight leads L₁ . . . L₈ are connected to a resistive network N_{HV}. Two deflection signal generators denoted by G_H and G_V are connected to network N_{HV}, which generators provide voltages U'_H and U'_V, respectively, varying in accordance with a sawtooth function. Some leads, namely L₁, L₃, L₅ and L₇ are connected to a resistive network N_F to which a direct voltage source D_F applies a focussing voltage U_F.

40 The difference between the voltages U_A and U_F determines focussing of the electron beam. If the voltages U_A and U_F were equal, focussing would not take place and the electrodes E₂ and E₃ would only be operative as anodes. A satisfactory focussing may be obtained, for example, with U_A = + 500 V and U_F = + 100 V.

45 55 For obtaining the deflection of the electron beam a voltage +U_V and -U_V is impressed on, for example, two segments such as S₁ and S₅ which are pairwise located and face each other relative to the tube axis K₄, which voltage U_V has a sawtooth variation with an amplitude of 50 V peak-to-peak. The combination of focussing and deflection then results in, for example, the segment S₁ conveying a voltage of 100 + 25 V and the segment S₅ conveying a voltage of 100 - 25 V.

60 65 The cathode-ray tube K₁ according to FIG. 1 is operative with its target plate K₂, which is formed, for example, with photosensitive material, as a television camera tube in which a scene to be picked up is displayed through an objective lens not shown on the target plate

K_2 . Any other embodiment of the tube K_1 is possible. The electrodes E_1 , E_2 and E_3 shown in the electrode system E may alternatively exchange positions.

In the description of FIG. 1 it has not been shown in detail how the control means shown outside the tube K_1 are active and particularly not how the electrode E_1 is controlled; FIG. 2 serves for this purpose. FIG. 2 shows that the resistive networks N_{HV} and N_F of FIG. 1 are formed as a combined bridge circuit N . In the bridge circuit N the reference R denotes resistors, B denotes branches and P denotes connection points. P_1 , P_2 , P_3 and P_4 denote four bridge connection points with the points P_1 and P_3 and P_2 and P_4 , respectively, facing each other being connected to two connection terminals (+ and -) of the deflection signal generators G_V and G_H , respectively. Bridge branches B_1 , B_2 , B_3 and B_4 are provided between the points P_1 and P_2 , P_2 and P_3 , P_3 and P_4 , P_4 and P_1 , respectively, which branches are each provided with two resistors R in series denoted successively by R_1 , R_2 , ..., R_7 , R_8 . The bridge circuit N according to FIG. 2 is provided with two cross branches which are located between points P_1 and P_3 and P_2 and P_4 , respectively, and are denoted by B_5 and B_6 . The branches B_5 and B_6 are each provided with four resistors in series R_9 ..., R_{12} and R_{13} ..., R_{16} , respectively. The branches B_1 ..., B_6 are provided with connection points P at the areas where two resistors R are connected together. Thus connection points P_{12} , P_{14} , P_{16} and P_{18} of the branches B_1 , B_2 , B_3 and B_4 are connected to the segments S_2 , S_4 , S_6 and S_8 , respectively. Two connection points P_{11} and P_{15} of branch B_5 are connected to the segments S_1 and S_5 , respectively, while two connection points P_{13} and P_{17} of branch B_6 are connected to segments S_3 and S_7 . Central connection points P_5 and P_6 of the branches B_5 and B_6 are connected together and are connected to the connection terminal of the focussing voltage source D_F which provides the focussing voltage $+U_F$.

It is found that the network N_F according to FIG. 1 corresponds to the resistors R_{10} , R_{11} , R_{14} and R_{15} of the bridge circuit N . The remaining resistors R of the bridge circuit N are incorporated in the network N_{HV} .

The bridge circuit N ensures that a required combination of the voltages provided by voltage source D_F and by one or both signal generators G_H and G_V is impressed on each of the electrode segments S_1 ..., S_8 while the source D_F and the generators G_H and G_V do not influence each other without extra steps being necessary therefor. By connecting source D_F to point $P_5 = P_6$, the focussing voltage $+U_F$ is impressed as a bias on the bridge circuit N , which voltage thus reaches all segments S_1 ..., S_8 through the resistors R_1 ..., R_{16} . Relative to the focussing (bias) voltage $+U_F$, the generators G_H and G_V decoupled through the bridge circuit N provide sawtooth varying voltages V'_H and U'_V whose mean value corresponds to the voltage U_F .

The following applies for the value of the voltages which are to be impressed on the electrode segments S_1 ..., S_8 located on the circumference of a circle in FIGS. 1 and 2 in order to obtain a deflection of the electron beam in the tube K_1 of FIG. 1 as linearly as possible. The starting point is a deflection of the electron beam in which the landing spot on the target plate K_2 as seen from the axis K_4 in the tube K_1 writes a line from the right to the left and in which a television raster corresponds to a deflection from the top to the bottom. Seen from the outside of the tube K_1 the deflection of a ras-

ter thus commences in the top-left corner of the target plate K_2 . It is assumed that in order to deflect the electron beam landing spot to the top, a voltage $+U_V$ across the segment S_1 is required and $-U_V$ across segment S_5 is required. For the deflection to the right there follows that a voltage $+U_H$ across the segment S_3 is required and $-U_H$ across segment S_7 is required.

For obtaining a satisfactory linear line deflection in which distortion is left out of consideration the segments S_2 , S_4 , S_6 and S_8 located on the circumference of a circle are provided and a combination of the voltages U_V and U_H is to be impressed on these segments. Calculated from the centre of the circle (at the area of $P_5 = P_6$ of the bridge circuit N) towards, for example, the centre of segment S_2 , an angle of 45° relative to the branches B_5 and B_6 is associated with the segment S_2 and a deflection voltage of $U_V/\sqrt{2}$ and $U_H/\sqrt{2}$ corresponds thereto. For the combination there applies that $(U_V + U_H)/\sqrt{2}$. Generally there applies that for an angle ϕ between the branch B_5 and a direction which varies clockwise, the deflection voltage at that area has the function: $U_V \cos \phi + U_H \sin \phi$ (1). Taking the given polarities of the voltages U_V and U_H into account, the deflection voltages shown in FIG. 2 follow for the segments S_4 , S_6 and S_8 .

In order to realize that the point P_{12} of branch B_1 of bridge circuit N connected to segment S conveys the voltage $(U_V + U_H)/\sqrt{2}$, the voltages U_V , $\sqrt{2}^2$ and U_H are to be impressed on the bridge connection points P_1 and P_2 , respectively. In fact, when it is assumed that no voltage from generator G_H is impressed on point P_2 and that resistors R_1 and R_2 have equal values, the resistors R_1 and R_2 operate as a divide-by-two circuit so that the voltage across point P_1 must be twice the voltage $U_V/\sqrt{2}$. Thus there follows that $U'_V = U_V/\sqrt{2}$. A similar reasoning yields for generator G_H : $U'_H = U_H/\sqrt{2}$.

It is found from the foregoing that the resistors R_1 and R_2 are equal and may have a value of, for example, 70 k.ohms. The same applies to resistors R_3 ..., R_8 . Resistors R_9 and R_{10} must have a value such that a voltage division from $U_V/\sqrt{2}$ to U_V is effected, hence $R_{10} : R_9 = 1 : (\sqrt{2} - 1)$. When resistor R_{10} is given a value of 65 k.ohms, approximately 27 k.ohms is the value for resistor R_9 . For reasons of symmetry there follows for the cross branch B_5 that $R_{10} = R_{11}$ and $R_9 = R_{12}$. A similar reasoning applies to resistors R_{13} ..., R_{16} in the cross branch B_6 , with $R_{13} = R_{16} = 27$ k.ohms and $R_{14} = R_{15} = 65$ k.ohms.

The focussing voltage $+U_F$ is impressed on all electrode segments S_1 ..., S_8 with the aid of the bridge circuit N and each segment separately receives a different deflection voltage without any mutual unwanted influence taking place. The position of the generators G_V and G_H may be interchanged without further steps. The bridge circuit N ensures in its simplicity a satisfactory focussing and deflection when the electrode system E and the electron gun K_3 as such do not cause deflection errors. Due to, for example, symmetry errors in the configuration of the system E and the gun K_3 relative to each other and to the tube axis K_4 , noticeable deflection errors may occur in practice. FIG. 3 shows a bridge circuit N in which some deflection error corrections can be performed while there are no principal deviations relative to the bridge circuit N according to FIG. 2.

In FIG. 3 two cross branches B_7 and B_8 are provided beyond the bridge branches $B_1 \dots B_4$ and the two cross branches B_5 and B_6 . The cross branches B_7 and B_8 provided between the connection points P_{12} and P_{16} of the bridge branches B_1 and B_3 and P_{14} and P_{18} , respectively, of the bridge branches B_2 and B_4 include two resistors R_{17} and R_{18} and R_{19} and R_{20} , respectively. Thus the segments S_2 , S_4 , S_6 and S_8 are connected to both a bridge branch B_1 , B_2 , B_3 or B_4 and to a cross-branch B_7 or B_8 . Unlike the bridge circuit N according to FIG. 2, the points P_5 and P_6 in FIG. 3 are not directly connected together but are connected together through a potentiometer R_{21} . Furthermore the points P_5 and P_6 are connected together through two series-arranged resistors R_{22} and R_{23} , while the junction of resistors R_{22} and R_{23} is connected to ground through a resistor R_{24} .

Branches B_7 and B_8 have connection points P_7 and P_8 , respectively, between the resistors R_{17} , R_{18} and R_{19} , R_{20} . As described with reference to points P_5 and P_6 a potentiometer R_{25} , two resistors R_{26} and R_{27} in series and a resistor R_{28} to ground are provided near points P_7 and P_8 . The wipers on potentiometers R_{21} and R_{25} are both connected to the output terminal of the focussing voltage source D_F . The potentiometers R_{21} and R_{25} form part of a bridge circuit R_{21} , R_{22} , R_{23} and R_{25} , R_{26} , R_{27} , respectively.

Since the potentiometers R_{21} and R_{25} produce a similar effect, this effect will be described with reference to the potentiometer R_{21} . When the wiper on potentiometer R_{21} occupies its central position, points P_5 and P_6 convey the same positive voltage which is active as a focussing voltage. Relative to this focussing voltage of, for example 100 V, the points P_{11} and P_{15} convey, for example, a more positive and a less positive voltage, respectively, of 25 V which are brought about by voltages $+U_V$ and $-U_V$. The same applies to, for example, points P_{13} and P_{17} which under the influence of the voltages $+U'_H$ and $-U'_H$ convey the voltages +125 V and +75 V respectively.

When the wiper on potentiometer R_{21} is moved towards point P_5 , the result is that the voltage across point P_5 increases and the voltage across point P_6 decreases by the same extent. It is assumed that a variation of 2.6 V is present, hence a voltage of 102.6 V at point P_5 and a voltage of 97.4 V at point P_6 . Assuming that there applies in FIG. 3 that $R_9 = R_{12} (= R_{13} = R_{16}) = 68$ k.ohm and $R_{10} = R_{11} (= R_{14} = R_{15}) = 50$ k.ohm, there follows that the voltage increase of 2.6 V across point P_5 yields a voltage increase of $50/50 + 68 \times 2.6 = 1.1$ V across both points P_{11} and P_{15} due to the voltage division across the resistors R_9 and R_{10} and R_{11} and R_{12} , respectively. For points P_{13} and P_{17} a voltage decrease of 1.1 V follows. The result is that the segments S_1 and S_5 , and S_3 and S_7 which prior to the displacement of potentiometer R_{21} corresponds to two equal electrical poles of opposite polarity have now acquired an extra positive and negative pole, respectively. This corresponds to a constant electrical quadripolar field which is superimposed on the two deflection fields varying in accordance with the sawtooth function. Such an electrical quadripolar field produces a given distortion of the electron beam landing spot on the target plate K_2 in the tube K_1 according to FIG. 1 dependent on the intensity and the polarity, hence the extent and the direction of the displacement of the wiper on potentiometer R_{21} . This distortion caused by the quadripolar field corresponds to the static astigmatism caused

by tolerances in the tube K_1 so that its correction is possible by causing the quadripolar field to produce an equally large, oppositely directed distortion.

It is found that the potentiometer R_{21} of FIG. 3 generates a quadripolar field as a function of the displacement from the centre, while the polar axes of this field are located in the direction of the segments S_1 , S_5 and of the segments S_3 , S_7 (FIG. 2). The intensity of the quadripolar field and the polarity is dependent on the magnitude and the direction of the displacement of the wiper on potentiometer R_{21} . To realize an error correction which is performed in an entirely correct manner it may be desirable to modify also the direction of the polar axes of the quadripolar field. To this end the branches B_7 and B_8 and the bridge circuit R_{25} , R_{26} , R_{27} are provided in FIG. 3. In the same manner as described with reference to potentiometer R_{21} a second quadripolar field with the polar axes in the direction of the segments S_2 , S_8 and S_4 , S_6 can be generated therewith (FIG. 2). By superimposition of the two quadripolar fields having 45° shifted polar axes, any quadripolar field for which given polar axis directions are required may be realized dependent on the direction and the extent of the displacement of potentiometers R_{21} and R_{25} .

It is found that the potentiometer R_{21} and the resistors R_{22} , R_{23} and R_{24} constitute a distributing circuit $R_{21} \dots R_{24}$ with which the focussing voltage across points P_5 and P_6 may be made different, while the mean value remains the same. There is also a distributing circuit $R_{25} \dots R_{28}$. By giving the resistors R_{24} and R_{28} unequal values, whereas the others have equal values, a voltage may occur between points P_5 and P_6 which is different from the voltage occurring between points P_7 and P_8 in case of an equally large displacement of the wipers on the potentiometers R_{21} and R_{25} . The distributing circuits $R_{21} \dots R_{24}$ and $R_{25} \dots R_{28}$ then have a difference in sensitivity.

The provision of the cross branches B_7 and B_8 according to FIG. 3 has a further advantage when a correction is required for a barrel or pincushion distortion which may occur in a raster shown on the target plate K_2 of FIG. 1. For reasons of symmetry one and the same value of, for example, 68 k.ohms has been taken for resistors $R_1 \dots R_8$, R_{12} , R_{13} and R_{16} . As already described a value of 50 k.ohms has been taken for resistors R_{10} , R_{11} , R_{14} and R_{15} . It follows from calculations that the voltages given in FIG. 2 occur in the segments S if the resistors $R_{17} \dots R_{20}$ likewise have a value of 50 k.ohms. By taking a value differing from 50 k.ohms for resistors $R_{17} \dots R_{20}$, the voltage across the segments S_2 , S_6 and S_4 , S_8 may be modified in such a manner that the distortion which becomes clearly manifest in the corners near the segments S_2 , S_4 , S_6 and S_8 is influenced. In case of pincushion distortion the deflection near the corners is to be attenuated relative to the linear deflection i.e., the segments S_2 , S_4 , S_6 and S_8 are to receive less voltage which may be satisfied by giving the resistors $R_{17} \dots R_{20}$ a lower value than resistors R_{10} , R_{11} , R_{14} and R_{15} . The opposite applies in case of barrel distortion.

It will be evident that not only the described static corrections but also dynamic deflection error corrections are possible. These corrections may be dependent for image field curvature and anisotropic astigmatism on the deflection voltages U_V and U_H and may comprise sum and difference terms or product terms of the deflection voltages. Such corrections may be applied as

voltages superimposed on the focussing voltage between the points P_5 and P_6 , and P_7 and P_8 .

FIG. 3 shows that dependent on a given construction of, for example, the deflection signal generator G_V a provision may be included to cause a direct current to flow through the branches B_5 , B_7 and B_8 of the bridge circuit N for shift purposes in the vertical direction. The generator G_V in FIG. 3 is formed with two generators G_{V1} and G_{V2} which are connected to ground with terminals of opposite polarity, while the remaining terminals are connected with respect to alternating current through capacitors C_1 and C_2 to the bridge connection points P_1 and P_3 . A series arrangement of two resistors R_{29} and R_{30} is arranged in parallel with the generator G_V to whose junction the voltage U_F is applied. A direct voltage source which includes a direct voltage source D_S and a potentiometer R_{31} is connected in parallel with resistors R_{29} and R_{30} . A displacement of the wiper on the potentiometer R_{31} which is connected to the resistor R_{30} provides the shift direct current through the branches B_5 , B_7 and B_8 . A direct current is not produced by the bridge circuit configuration in the branch B_6 as is evident in a simple manner from FIG. 2. By connecting in a similar manner an adjustable direct voltage source (D_S , R_{29} , ..., R_{31}) in parallel with the bridge connection points P_2 and P_4 , a horizontal shift direct current through the branches B_6 , B_7 and B_8 may be obtained while no direct current is produced through branch B_5 .

Instead of the embodiment of the adjustable direct voltage source D_S , R_{29} , ..., R_{30}) shown the required direct voltage may alternatively be derived directly from the focussing voltage U_F .

FIG. 3 shows that capacitors C_3 ..., C_8 are arranged in parallel with the resistors R_2 , R_3 , R_6 , R_7 , R_{13} and R_{16} . These capacitors C_3 ..., C_8 are not principally required for the invention, but they are to be provided when, as is shown in FIG. 1, the cable L is used. The leads L_1 ..., L_8 of the cable L have their own capacitance which together with the capacitance of the segment S connected thereto in tube K_1 may yield a composite capacitance of approximately 50 pF. Since as shown in FIG. 2 the generator G_V provides a low frequency sawtooth voltage of, for example, 50 or 60 Hz for the deflection in the vertical direction, the influence of the composite capacitance at this low frequency is negligible. This, however, does not apply to the line deflection in the horizontal direction to which end the generator G_H provides a high frequency sawtooth voltage of 15625 or 15750 Hz. Since the composite capacitance of the lead L_3 and of the segment S_3 is present in parallel at the bridge resistor R_{14} and calculated for example from point P_{13} , the capacitor C_7 is to be arranged in parallel with resistor R_{13} for the sake of a satisfactory bridge equilibrium. The same reasoning applies to all capacitors C_3 ..., C_8 .

In that case there applies that the said composite capacitors per segment S and the associated lead of cable L need not all have the same value so that the capacitors C_3 ..., C_8 are to be adapted and may for this purpose be formed in an adjustable manner.

For obtaining a low dissipation in the bridge circuit N it is favourable to give the resistors R_1 ..., R_{20} a high value. The result is that charging and discharging of the said composite capacitors is effected through a long RC-time constant. For the sweep in the high frequency sawtooth voltage U'_H the time constant does not pro-

vide difficulties, but in case of a short-lasting flyback discharging of the said capacitors cannot be effected as fast as possible. For realizing a sufficiently fast discharge of the capacitors the use of capacitors C_3 ..., C_8 is most desirable.

If the cable L of FIG. 1 were to have a negligibly low capacitance or if it were absent because, for example, the bridge circuit N shown in FIG. 2 is provided in an integrated form on or near the tube K_1 , capacitors C_3 ..., C_8 of FIG. 3 could be omitted.

In case if integration of the resistors R of the bridge circuit N they may be provided in or outside the tube K_1 on its wall near the electrode E_1 .

FIG. 4, likewise as in FIG. 2, shows a bridge circuit N which is, however, suitable for use with an electrode E_1 which is built up from six segments S . As compared with FIG. 2 it is found that the segments S_3 and S_7 are omitted and the remaining six segments S_1 , S_2 , S_4 , S_5 , S_6 and S_8 as seen along the circumference of a circle have a longer form. Since the segments S_3 and S_7 of FIG. 2 are absent, the cross branch B_6 is likewise absent.

Calculated from the centre of the circle which corresponds to the connection point P_5 of the cross branch B_5 to which the focussing voltage U_F is applied an angle ϕ of 60° (point P_{12}) is associated with segment S_2 in FIG. 4.

In this case the angle ϕ relates to formula (1) given with reference to the description of FIG. 2. Angles which are an integral multiple of 60° are associated with the subsequent segments S_4 , S_5 , S_6 and S_8 . While using the manner shown in FIG. 2 of calculating the required various voltages in the bridge circuit N at which the voltage U_H is fictitiously present, because the segments S_3 and S_7 are absent in FIG. 4, it follows for the segment S_2 that: $U_V \cos 60^\circ + U_H \sin 60^\circ = \frac{1}{2}U_V + \frac{1}{2}U_H \sqrt{3}$. By drawing a tangent in point P_{12} to the circumference of the circle on which the segment S_2 is located, the voltages can be calculated which are to be impressed on the points P_1 and P_2 so as to obtain the desired voltages across the segments S . Starting from $+U_V$ on segment S_1 a voltage of $+U'_V = 2U_V$ follows for point P_1 . When assuming the fictitious voltage $+U_H$ to be present at the area between the segments S_2 and S_4 , it follows for point P_2 that $+U'_H = 2U_H/\sqrt{3}$. As shown in FIG. 2 the voltages across the other points P are found in FIG. 4 by including the + and - polarities.

Since the bridge branches B_1 , B_2 , B_3 and B_4 are identical, two resistors are denoted by R_{32} and R_{33} of the bridge branch B_1 only. Since the cross branch B_5 is identical on either side of point P_5 , two resistors are denoted by R_{34} and R_{35} which are located between the points P_1 , P_{11} and P_5 . Since the resistors R are to have a ratio which is the same as the length of the line sections of the bridge circuit N in which they are shown it follows that $R_{34} = R_{35}$ and it follows from R_{32} ; $R_{33} = \sqrt{3} : 1/\sqrt{3}$ that $R_{32} = 3R_{33}$.

In the manner as described in FIGS. 2 and 4 the required ratios of the resistors R in the bridge circuit N can be calculated in a simple manner, dependent on the number of segments S of the electrode E_1 .

Likewise as in FIG. 4 the segments S_3 and S_7 of FIG. 2 are absent, the segments S_1 and S_5 might be omitted in FIG. 2 although the deflection will be effected less linearly even when enlarging the remaining segments S_2 , S_4 , S_6 and S_8 . Dependent on the imposed requirements this may be allowed. When the segments S_2 , S_4 , S_6 and S_8 are present the cross branches B_5 and B_6 are

omitted and instead the cross branches B_7 and B_8 shown in FIG. 3 are to be provided between the points P_{12} , P_{16} and P_{14} , P_{18} . The focussing voltage U_F is again applied to the central connection points P_7 and P_8 in this case.

As compared with a conventional arrangement of four deflection electrodes located in the two transverse deflection directions which correspond to the use of only the segments S_1 , S_3 , S_5 and S_7 according to FIG. 2, the use of only the segments S_2 , S_4 , S_6 and S_8 which are located between the said deflection directions has the advantage that at the area where the greatest problems for a linearly varying deflection field occur, namely in the corners, the presence of the segments at that area reduces the problems.

What is claimed is:

1. An electrostatic deflection and focussing circuit for a cathode ray tube including a plurality of opposite electrode segments symmetrically arranged about a central axis, comprising in combination, a bridge circuit having two pairs of opposite junctions connected to assigned pairs of electrode segments, two sources of deflection signals each connected to a pair of said junctions, a crossed connection of four resistances having a common point and four terminal points connected to said junctions, respectively, and a source of a focusing voltage having a terminal connected to said common point.

2. A circuit as claimed in claim 1, characterized in

that a distributing circuit to which the focussing voltage source is connected is provided between the common point of the said crossed connection, which distributing circuit causes an inequality in the voltages applied to the common point.

3. A circuit as claimed in claim 2, characterized in that the distributing circuit is formed with a bridge circuit including a potentiometer which is arranged between the said common point, while a wiper on the potentiometer is connected to the focussing voltage source.

4. A circuit as claimed in claim 1, characterized in that a deflection signal generator having output terminals coupled by capacitors to the bridge junctions and an adjustable direct voltage source connected in parallel to said junctions for supplying a shift direct current.

5. A circuit as claimed in claim 4, characterized in that capacitors are arranged in parallel with the resistors which are connected to those bridge junctions and are connected to the deflection signal generator which provides a voltage of a higher frequency.

6. A circuit as claimed in claim 1, characterized in that the bridge circuit is provided with resistors in integrated form mounted on the cathode ray tube.

7. A cathode-ray tube provided with a deflection circuit as claimed in claim 6, characterized in that the resistors are provided in an integrated form on the wall of the cathode-ray tube.
